UNITED STATES PATENT OFFICE.

ALLEN A. RUSSELL AND HARLEY A. RUSSELL, OF INDIANAPOLIS, INDIANA.

HOOD FOR PNEUMATIC STACKERS.

SPECIFICATION forming part of Letters Patent No. 660,591, dated October 30, 1900.

Application filed December 26, 1899. Serial No. 741,594. (No model.)

To all whom it may concern:

Be it known that we, ALLEN A. RUSSELL and HARLEY A. RUSSELL, citizens of the United States, residing at Indianapolis, in the county 5 of Marion, and State of Indiana, have invented certain new and useful Improvements in Hoods for Pneumatic Stackers, of which the following is a specification.

This invention relates to improvements in 10 the discharge-pipes of pneumatic straw-stackers, and has reference particularly to the construction and operation of the hood at the outer end of the pipe, by means of which the direction of the discharge is controlled.

15 This invention is an improvement on the hood shown and described in Patent No. 601,356, issued to A. A. and H. A. Russell March 29, 1898.

One object of this invention is to provide a 20 very simple, inexpensive, and durable means of attaching the hood to the discharge-pipe in a revoluble manner to permit of free and easy turning of the discharge-opening to right or left to give the straw a lateral direction as 25 discharged and, while providing a free-acting joint, to avoid the accumulation of heavy material in its construction. This last matter of lightness is very important, because every ounce at the end of the long discharge-pipe 30 is greatly multiplied by the long leverage and adds rapidly to the difficulty of handling the pipe and hood.

The further object is to provide a hood made out of a series of hinged 35 and folding hollow spherical segments held open by a spring constructed to avoid interfering with the discharge of the straw from the mouth of the hood.

The object also is to provide various improvements in the details of the construction, 40 such as will be fully described, and pointed out in the claims.

We accomplish the objects of the invention by the mechanism illustrated in the accompanying drawings, in which—

45 Figure 1 is a detail view in perspective of the discharge-pipe of a pneumatic stacker having our invention; Fig. 2, a like detail in side elevation, showing the hood in its contracted or folded position; Fig. 3, a transverse section on the dotted line 3 3 of Fig. 2, and

Fig. 4 a longitudinal vertical central section of Fig. 1.

Like characters of reference indicate like parts throughout the several views of the 55 drawings.

A represents the discharge-pipe, which will be made of a plurality of hollow cylindrical sections, each of which has a bead near one end to stop the end of the adjacent section 60 when the latter is slipped on the narrow annular portion outside of the bead of the beaded pipe. The part A is slipped upon the part A' until arrested by the bead on the latter. Then the lapped ends are riveted together, as 65 shown at a, Fig. 1.

A' represents the last or outer section of the discharge-pipe. It will have the externally-projected annular bead a' near its outer end to form a guide and lock for the first section 70 B of the hood. The section B has the externally-projected annular bead b, adapted to fit over the bead a', permitting rotary adjustment of the section B, but preventing its withdrawal or separation from the section A'. To 75 enable the outer section to be fitted over the inner one, the former is split longitudinally on one side, enabling its walls to be spread, after which they are united by means of a two-part casting d d, the bases of each of which parts are 80 preferably slotted to straddle the bead and follow the outside contour of the section B, to which they are riveted. Then they each have radial outwardly-projected plates, which contact with each other and are bolted together after the beaded hood-section is in 85 place on the beaded last section of the discharge-pipe. The bolt is represented at d', and d' is a hole through the plates for the attachment of the cables c for rotating the hood. 90

These cables are, as usual, two in number, one passing to the right and the other to the left around to the top of the pipe and are rove through a slotted cast-iron block E, riveted to the top of the section A' and having friction-pulleys e e to ease the turn of the cables to the rear. The cables are carried down to the bottom of the pipe and are fastened to the drum of a windlass or otherwise taken care of in the usual manner.

95 Running from the split side of section B in lines parallel with the bead and adj-

cent to it are splits b' , extending approximately half-way around the pipe from the longitudinal split. These splits b' run each way from the longitudinal one, and the lower walls of section B thus released are straightened out, as shown in Fig. 3, to provide an under side opening, which forms part of the outlet or mouth of the hood. A gore of sheet metal b^2 is set in to close the gap between the straightened and old circular walls. A portion of the bottom of this straightened wall is cut away.

To the outer end of section B is secured a hollow spherical segment 1, which will preferably be riveted fast to said section B. Pivoted at f to segment 1 is a similar segment 2. Pivoted to segment 2 is segment 3, and pivoted to segment 3 is segment 4, any desired number of segments being introduced in like manner to form an adjustable elbow of the desired angle, enough being used, preferably, to cause the wall of the last segment opposite the chute to stand at least vertically, if not to incline inwardly, toward the chute at all ordinary angular elevations of the latter. This is to counteract the tendency of the straw to shoot off from the mouth of the hood at such an angle when discharged as to make a stack of too much obliquity on the far side from the machine, the objection being that it permits animals to climb up easily and waste the straw. It will be noted that the pivotal points f for the several segments are at varying distances from the ends of the segments, the pivotal points of the middle segments being the greatest distance in from the ends of the segments. This is to cause the lower or end segments of the hood to draw in closer to the main pipe, thus making the front wall nearer vertical than would otherwise obtain. The last segment 9 is preferably wider than the rest and will be strengthened and stiffened by the semicircular bead g . This section is more exposed to hard usage than any of the others and much annoyance has been occasioned by the mutilation of this last segment. This is remedied by the beaded formation.

H represents springs (only the one on the near side is shown) made from strap-steel bent at the inner end h where attached to the hood-section B in a manner to present the thin edge of the strap out. The front end of the spring has an eye, which is fastened to the post i , attached to the segment 9. The spring is set and tempered to a curve, as shown in Fig. 1, tending normally to draw out or unfold the hinged segments. The curvature of the spring places it always away from the mouth of the chute along the side of the latter out of reach of the discharging straw. To increase the efficiency of the spring's action, we prefer to rivet the last three segments 7, 8, and 9 together by connecting them by means of a strap of metal j . To keep the springs H from opening the segments too far, we attach a chain J to the outer end of section B at b^2 and

to segment 7 at b^7 , and then secure it at intermediate points to the intervening segments, as shown. At b^3 and b^7 are rings or eyelets, to b^7 of which a cable c^2 is fastened, which after passing through eyelet b^3 is continued down to the base of the chute to a windlass or other usual and suitable holding means. To keep the cable c^2 from mixing and interfering with cables c and their block and pulleys, we throw the fixed bail m over them in the manner as clearly shown in the drawings.

Having thus fully described our invention, what we claim as new, and wish to secure by Letters Patent of the United States, is—

1. The combination with the discharge-pipe of a pneumatic stacker having an annular outwardly-projected bead near its outer end, of a hood-section mounted on said tube having an externally-projected annular bead to engage the bead of the discharge-pipe, said hood-section being split longitudinally on one side to allow the walls to be spread for assembling and a two-part block each part having a base fastened to the wall of the hood-section, one on either side of the split and each base having an outwardly-projecting flange or plate and a bolt for uniting the plates, substantially as shown.

2. An adjustable hood for straw-stackers comprising a body-section split longitudinally on its under side and having its under walls partly cut away and straightened to plane surfaces and having a gore between the plane and adjacent cylindrical surfaces, a series of hollow spherical segments the first of which is secured to the body-section of the hood and each of the following segments to the segment immediately preceding it, some of said segments being pivotally attached to allow a folding adjustment thereof, the last segment having a longitudinal corrugation, said folding segments being connected by a flexible tie, all substantially as described and shown.

3. A hood for pneumatic straw-stackers having a body-section the inner end of which is cylindrical and the major outer portion of which has a semicylindrical top passing into sides which are plane surfaces, the bottom being open, a hollow spherical segment secured to the outer end of the body-section, a similar segment pivotally secured to it and a series of following segments each of which is secured by separate attachment to its adjacent segment some of them pivotally as shown, said pivotally-connected segments being also connected by a flexible tie as shown and a pair of normally-curved strap-springs fastened at one end to one of the outer segments and at the other to the body-section of the hood, said springs being always above the mouth of the hood and tending to separate the segments, as and for the purposes specified.

4. In a hood for stackers, the combination with a body-section and a series of adjustable

5 pivotally-secured sections, of a pair of strap-
steel springs attached to one of the outermost
pivoted sections at one end and to the body-
section at the other, said springs being nor-
mally curved to give the pivoted sections a
maximum separation and being always above
the mouth of the hood, substantially as de-
scribed.

5. The combination with an inclined chute,
10 of a hood in a plurality of sections, said sec-
tions being widest at their middles, pivots
connecting the sections, the edge of each sec-
tion near both of its ends being pivotally se-
cured to the edge of the next adjacent section

and not more than two sections being con- 15
nected by the same pivot, said pivots from the
middle to the outside sections being a gradu-
ally-lessening distance from the ends of the
sections, substantially as described and speci-
fied.

In witness whereof we have hereunto set
our hands and seals at Indianapolis, Indiana,
this 22d day of December, A. D. 1899.
